UNITED STATES PATENT OFFICE.

LEANDER W. WOOD, OF FONTANELLE, IOWA.

COMBINATION ACCEPTANCE, ORDER, AND PLURAL CHECK BLANK WITH INDEX-KEYS.

1,299,647.

Specification of Letters Patent.

Patented Apr. 8, 1919.

Application filed March 18, 1918. Serial No. 223,069.

To all whom it may concern:

Be it known that I, LEANDER W. Wood, a citizen of the United States, and resident of Fontanelle, in the county of Adair and State 5 of Iowa, have invented a certain new and useful Combination Acceptance, Order, and Plural Check Blank with Index-Keys, of which the following is a specification.

The object of my invention is to provide 10 a combination acceptance, order and plural check blank with index keys, of simple, durable and inexpensive construction.

More particularly it is my object to provide 15 a combination blank having arranged thereon certain printed matter and certain blanks in different logical arrangement with relation to each other, whereby a proper record may be kept of a number of business transactions.

20 A further object is to provide such a blank having printed matter and indicating characters arranged thereon in such a manner as to enable the user to keep a record of business transactions and do away with the keeping of a number of books of account and the like.

Still a further object is to provide such a 25 blank and index key which may be used to record an order for goods, the agreed price and the discount terms, and an agreement to pay, with an indication of the bank of the payer, and to provide as a part of such a blank a stub record.

With these and other objects in view my 30 invention consists in the construction, arrangement and combination of the various parts of the device, whereby the objects contemplated are attained, as hereinafter more fully set forth, pointed out in my claim and 35 illustrated in the accompanying drawings, in which:

Figure 1 shows a plan view of the face of my improved combination blank.

Fig. 2 shows a plan view of the reverse 40 side thereof illustrating matter which may if desired, be printed on the face of the blank; and

Fig. 3 shows a plan view of a portion of a blank showing a slightly modified form of 45 the index key.

It will be understood that the blanks may be arranged in pads, in a book or holder and comprise in each case preferably a stub A and a body B. A scored or perforated line,

indicated by the reference character 10, is 55 provided at the edge of the stub.

On each stub I preferably provide indicating characters 11 showing the date, with a blank 12 adjacent thereto. There are also provided on the stub indicating characters 60 "Name," "Amount," "Acceptance dating," "Deposited," "Stock," "Collection" and "Paid" with blanks adjacent thereto. Dotted lines may be provided for the blanks.

There is also provided on the stub, indicating characters 13 which may be the letters A, B, C and D for a purpose which will hereafter be more fully referred to.

On the body B of the blank there is provided an address line 14 with a date line 70 blank 15 adjacent thereto. On the body is provided indicating characters, such for instance as "Acceptance date" or an abbreviation therefor indicated by the reference character 16 and the blank line 17 adjacent 75 thereto.

There is preferably also provided a blank line 18 followed by "Thirty days" or similar indicating characters, a dollar sign and a blank 19.

80 Adjacent to the blank 19 is a blank line 20 preferably followed by the word "Order."

Suitably located are indicating characters for the word "Number" indicated by the reference character 21 and followed by a 85 blank line 22.

Suitably arranged on the face of the body B of the blank is the word "Dating" followed by a blank line 23.

Suitably arranged on said blank is the 90 word "Discount" or an abbreviation thereof and a blank line 24 adjacent thereto; also suitably arranged are the words "Any bank or payor" and underneath said words are the words "Pay to endorser \$_____" followed by the blank space 25. Adjacent to the words "Any bank or payor" is the word "Depository" or its equivalent, and if desired the names of certain banks such for instance as "First National and State Sav- 100 ings."

The names of the banks are preferably arranged in column form and are followed by indicating characters such as A, B, and so forth. In the column just indicated is a 105 blank line 26 followed by a further indicating character such as C. Adjacent to the blank 25 are the words "The under-

signed will pay to holder the amount of this order, less 2 per cent. one, 1 per cent. 20, net 30 days, paid at depository" or their equivalents, and the last named words are 5 followed by a blank line 27.

Suitably arranged on the blank is a blank signature line 28.

Suitably arranged also may be a blank line 29 followed by the indicating characters "Lbs" or other suitable characters.

Suitably arranged also is a blank line 30 preferably preceded by the dollar sign and followed by the indicating characters A, B, C and D or the like, similar to the indicating characters 13 on the stub.

In Fig. 2 I have shown an index key which may be printed on the back or on the face of the body of the blank as may be desired. This index key may have the 20 words and letters shown, or others which would satisfactorily explain the use of the key letters hereinbefore referred to. In Fig. 3 I have shown a different form of the index key, which, it will be seen, occupies 25 very little space and could be placed on the face of the blank.

On the back of the blank there may be printed, if desired, suitable lines for the payee and payer.

30 In explaining the use of my improved combination blank, it may be said that some of the indicating characters mentioned and some of the blank lines indicated are optional and may be used or not, and that 35 some of the indicating characters and blank lines are used for recording some transactions while others are used for recording other transactions.

An important feature in connection with 40 my blank arises from the fact that these various indicating characters and blank lines are suitably and conveniently arranged on a single sheet making it possible with the single sheet to record a large number 45 and variety of transactions.

For the sake of illustrating the advantages of my improved combination blank and the variety of uses to which it may be put, I will mention two different transactions and explain the method of recording them, and in connection therewith will mention some of the further advantages of 50 my blank.

Assume that a retail dealer sells to a 55 customer a load of coal. The stub is filled out with the date, the name of the customer and the amount of the purchase. If later on the body of the blank is deposited in the bank or otherwise, the blank following the word "Deposited" on the stub may be filled out. If the body of the blank is sent to a bank for collection, the blank following the word "Collection" may be filled out to properly indicate the transaction.

65 The blank following the word "Paid" on

the stub may be filled in with the word "Cash" if the transaction is for cash, or may receive a check if payment is to be made at a later time, or with any other proper indicating word or character.

For the transaction now under consideration, the body of the blank might be filled out as follows:

The date line is filled in with the date of the transaction. The blank 19 is filled 75 out with the amount of the transaction. The blank 29 is filled in with the quantity, that is the number of pounds, and the blank 30 is filled in with the amount of the transaction. The blank 25 is filled in 80 with the amount of the transaction, less the discount allowed. The purchaser signs in the blank 28.

The blank 27 is filled out with the key letter indicating the bank where the purchaser deposits or makes his checks.

If the purchaser banks at one of the banks indicated in the column, such for instance, as the First National Bank, then the key is followed and an X is placed above 90 the A on the stub, also above the A following the blank 30, and also above the A following the words "First National". In this case the letter A would be inserted in the blank 27.

It will be noted that in any case the blank, when filled out, constitutes a signed order, and when filled out to indicate a bank will show the bank through which the purchaser expects to make payment.

Assume that the same merchant desires to order a bill of goods through a jobber. He fills in the stub with the proper data. In the body of the blank the merchant may fill in the date line 15 with the date of the order, 105 or if he desires to provide for a future payment and to make a promise to pay at that date, the date line 15 may be filled out with the future date. For instance, if the merchant desires to enter his order for goods 110 on the first of February, but desires to make payment on the first of May and such is the arrangement with the jobber, the date line 15 will be filled in with the date May 1st. The blank 19 will receive the amount of the order 115 and the same amount will be inserted in the blank 30. The blank 25 will receive the amount of the order less the maximum discount. The blank 20, in case of any transaction, may be filled in with indicating characters 120 showing the general nature of the transaction.

The merchant may check his bank such, for instance, as the First National Bank, follow the key and place an X above the A.

If the merchant desires to make a check on the blank he places a dash above the letter or indicating character following the name of his bank, for instance, above the A and places a similar dash above the A following 130

the blank line 30 and above the A on the stub.

It will be noted in the case of either of these transactions or a large number of other 5 transactions which might be recorded on my improved blank, an instrument is completed which can be deposited by the holder at a bank for credit or for collection, and which makes a complete record binding upon the 10 person whose name is signed in the space 28.

It is of course possible that these instruments might pass from hand to hand as notes or checks do.

As has already been indicated a vast number 15 of transactions may be recorded with my improved blank. Both the stub and the body may make practically permanent records.

It will be noted in this connection that the 20 use of my combination blank makes it possible to do away with a large amount of bookkeeping.

My combination acceptance order and plural check blank takes the place of a large 25 number of different blanks which might otherwise be necessary.

It will be noted that where my blank is used it always accomplishes a number of functions. That is to say it records the 30 amount of the transaction; the terms of payment including the discount; the day of payment; the agreement to pay; the nature of the transaction; the bank at which the purchaser does business.

35 Where desired the blank may also be made to indicate the disposition of the instrument such for instance as deposited for collection, or deposited for credit.

The use of my blank makes it possible to 40 accomplish extensive record keeping with a minimum of labor and expense.

It is believed that it is new in its typographical construction.

Attention is also called to the advantage 45 of the use of the key which makes it possible to indicate a variety of transactions and facts with a minimum of bookkeeping labor.

I have produced a typographical construction and form of combination blank 50 and index keys therefor which accomplishes more than one function at a time.

Some changes may be made in the arrangement of the indicating characters of my improved combination blank without departing from the essential spirit and purpose of my invention, and it is my intention to cover by my claim any modified form 55 of arrangement or use of equivalent arrangements which may be reasonably included within the scope of my claim. 60

I claim as my invention:

A combination blank comprising a stub having thereon indicating characters for recording a transaction including key characters, a body having a date line, and having 65 blanks for the amounts of the transaction, words for indicating any bank or payer, indicating characters for banks, and a blank adjacent thereto, key characters adjacent to said last indicating characters and blank, 70 the words "Pay to the endorser" followed by a blank, characters indicating substantially that the undersigned will pay to holder the amount of this order, a blank line for signature, key characters adjacent to one 75 of the blanks for the amounts, an index key indicating the uses of said key characters, and indicating characters for showing discount agreements.

Des Moines, Iowa, February 19, 1918.

LEANDER W. WOOD.
